UNITED STATES PATENT OFFICE.

WILLIAM C. HICKOX, OF SAYRE, PENNSYLVANIA.

CHEMICAL FIRE-EXTINGUISHER.

SPECIFICATION forming part of Letters Patent No. 752,072, dated February 16, 1904.

Application filed February 17, 1903. Serial No. 143,845. (No model.)

To all whom it may concern:

Be it known that I, WILLIAM C. HICKOX, a citizen of the United States, residing at Sayre, Pennsylvania, have invented certain new and 5 useful Improvements in Chemical Fire-Extinguishers, of which the following is a specification.

My invention relates to automatic and manually-operated fire-extinguishers of the general class disclosed in an application for Letters Patent of the United States, filed by me September 18, 1902, Serial No. 123,950.

My present invention relates more particularly to the arrangement of the acid-bottle, 15 its construction, and the means for insuring its breakage upon the manual or automatic operation of the device.

In the accompanying drawings, Figure 1 is a central vertical section of the invention. 20 Fig. 2 is a sectional plan view of the acid-bottle; Fig. 3, a vertical sectional view of the acid-bottle; Fig. 4, a detail view relating to the three-way valve and the nozzles connected therewith. Figs. 4^a and 4^b are further details 25 of this valve. Fig. 5 is a detail view of a modified arrangement of nozzles and means for automatic control. Fig. 6 is a view, similar to Fig. 5, of another modification. Fig. 7 is a detail view of the controlling-valve when 30 the movable nozzle is in a different position from that shown on Fig. 4^b.

Referring to Figs. 1 to 4, the main tank 1 is of substantially the form shown in my application above referred to, having a cover 35 2, provided with depending supports 3, from which are supported the hangers 4 of a cage 5, which contains the acid-bottle 6, the said bottle having a conical lower end 7, the apex of which projects downwardly between a series of inwardly-extending fingers or points 8 of the supporting-cage, the said fingers being intended to aid in fracturing the bottle for the discharge of its acid contents into the contents of the tank. A plunger 9 extends through 40 the cover, and the downward operation of this plunger is intended to effect the breakage of the acid-bottle. The plunger at its upper end has a handpiece 10, and it is associated with a lever 11, pivoted at 12 to a standard 13, extending up from and secured to a lug 14 on

the tank, the said lever at its intermediate portion resting upon a pin 15 on the plunger and at its free end being sustained by a fusible plug 16, extending through an opening in a standard 17, extending up from a lug 18 on 55 the top of the tank, to which lug the standard is screwed. A spring 19 is connected with the lever near its free end and also to the top of the tank, the tendency of which spring is to draw the lever downwardly and thrust the 60 plunger down, so as to break the bottle. The plunger is adapted to have movement independent of this lever, for which purpose it is provided with the handpiece 10, above referred to; but it is held normally up by a 65 spring 19', arranged between the handle and the lever. By striking the handpiece a blow or exerting pressure thereon it will be forced downwardly, and the head 20 on its lower end will strike a cross-bar 21 of a U-shaped breaking device 22, which comprises, in addition to the cross-bar 21, vertically-extending arms 23, depending therefrom.

As shown in Figs. 2 and 3, the acid-bottle is provided with grooves 24 in its opposite sides, 75 and in these grooves the vertically-extending arms of the U-shaped breaking device are arranged. As shown in Fig. 3, the grooves 24 of the acid-bottle do not extend through to the bottom surface thereof, but terminate in 80 shoulders 25, upon which the lower ends of the vertical arms of the U-shaped breaking device rest. It will thus be seen that when the plunger 9 is forced downwardly and strikes the U-shaped breaking device it forces the 85 same downwardly, causing the lower ends of the vertical arms to exert a pressure or strike a blow upon the shoulders 25, so as to break the bottle at this point. It will be seen that this arrangement is of particular importance 90 for the reason that the bottle is broken at its lower end, thus insuring the discharge of its whole contents into the liquid of the tank—a result which does not always occur by the impact of a plunger upon the upper end of the 95 bottle, in which arrangement it might happen that the upper part of the bottle is broken and the lower part remains intact, thus retaining a quantity of the acid.

As in my former application, I employ here- 100

in a screen 26, surrounding the cage and the acid-bottle, to catch fragments of the bottle, and this screen may be supported by clasps or hooks 26^x from any suitable part of the cage, 5 the said clasps being arranged to permit the ready removal of the screen from the cage.

For the discharge of the fluid I provide a plurality of nozzles and a three-way valve or cock controlling the same. One of these nozzles is shown at 27 connected to a three-way valve 28, adapted to rotate in a casing 29, connected to a pipe 30, extending into the tank and to the lower part thereof for the discharge of the fluid. A second nozzle 31 is connected 15 with the casing 29 and is in fixed relation to the tank and adjacent parts. This latter fixed nozzle is in communication through the three-way valve and pipe 30 with the interior of the tank under normal conditions, so that should 20 the plunger be operated at any time by the automatic device—*i. e.*, the fusible plug 16 and the spring 19—the fluid and gas will be discharged through the fixed nozzle 31. This nozzle is provided with a series of holes 32 in 25 its end adapted to send the fluid in a plurality of directions to cover a large area. If, however, it is desired to direct the fluid by means of the movable nozzle, this is raised from its normal position, and in this raising action it 30 turns the plug of the valve 28 and cuts off communication between the fixed nozzle 31 and the tank, so that then the fluid will pass out through the pipe 30, the three-way valve 28, and the movable nozzle to the point desired, 35 it being understood that the movable nozzle may have a flexible section to enable the stream to be directed to any desired point. Normally the movable nozzle depends along the side of the tank and its weight is sufficient to turn the 40 three-way valve so as to cut off communication between this and the tank and open communication between the tank and the fixed nozzle.

I do not wish to limit myself to the form or 45 arrangement of nozzles shown. It will be seen that the movable nozzle is in a sense an automatic controlling device, which when raised for the purpose of directing the stream cuts off the fluid from the fixed nozzle and 50 opens communication between this and the tank for the discharge of the fluid.

In Fig. 5 I show an automatic arrangement whereby a tank located in one compartment or chamber may be controlled automatically 55 from the temperature or by the presence of fire in another room and whereby also the extinguishing fluid may be directed from said tank into the other room. In this arrangement the automatic lever above described is 60 supported by a rod 33, which in turn is supported by a fusible plug 34, located in an adjoining room, the said rod 33 extending through an opening 35 in the floor or partition. This fusible plug is suitably supported, 65 and it in turn supports the rod 33 until the

heat of the fire is sufficient to fuse the said plug, when the rod 33 will fall, causing the automatic operation of the extinguisher and the discharge of the fluid through the pipe 36, which extends through the floor or partition 70 and is provided with any suitable sprinklers 37, as shown.

Referring to Fig. 6, I may provide a weight 38, held up by a cord or chain 39, passing over a pulley 40 and down to a fusible plug 75 41, suitably supported in the adjoining room or compartment, so that by the fusing of this plug or by burning the cord the weight 38 will be released and, falling upon the plunger 9', will break the acid-bottle, and the extinguishing fluid will be discharged through pipe 80 36 and sprinklers, as in the form last described.

It will be understood that I do not wish to limit myself to the use of a spring as the 85 means for automatically operating the lever, because a weight may take the place of the spring with equally good effect or the two may be used together, the weight being slipped onto or hung from the lever, as indicated at X. 90

I claim as my invention—

1. In combination in a chemical fire-extinguisher, a tank, an acid-bottle therein having supports or ledges at or near its lower end and a breaking device arranged to contact 95 therewith, substantially as described.

2. In combination in a chemical fire-extinguisher, a tank, an acid-bottle, means for supporting the same within the tank, a movable breaking device engaging the lower part of 100 the bottle, the said supporting means comprising a series of points to aid in breaking the lower part of the bottle and means for operating the breaking device, substantially as described. 105

3. In combination in a chemical fire-extinguisher, a tank, an acid-bottle supported therein and means for breaking the said acid-bottle extending downwardly along the side thereof to contact with a portion of the said bottle 110 below its top and means for operating the said breaking device, substantially as described.

4. In combination, a tank, an acid-bottle supported therein and a U-shaped breaking device having its arms extending down along 115 the side of the acid-bottle and engaging the lower part thereof, substantially as described.

5. In combination with a tank, an acid-bottle having grooved sides with ledges or projections at the lower ends of the said grooves 120 and a breaking device arranged in the said grooves, substantially as described.

6. In combination a tank, an acid-bottle supported therein having a grooved side and a breaking device arranged in the said groove 125 and contacting with the lower part of the bottle to break the same, substantially as described.

7. In combination a tank, an acid-bottle supported therein having a conical lower end, a 130

cage having inwardly-extending points to engage the conical lower end and a breaking device extending down along the side of the bottle and engaging a portion thereof below its top, substantially as described.

8. In combination with a tank, an acid-bottle, a cage for supporting the said acid-bottle and a screen inclosing the cage with clasps to fasten on upper edge of cage to hold the

screen removably in place, substantially as described.

In testimony whereof I affix my signature in presence of two witnesses.

WILLIAM C. HICKOX.
